HINGE

John Ludwig, Detroit, Mich.

Application February 10, 1936, Serial No. 63,148

8 Claims. (Cl. 16—164)

My invention relates to a new and useful improvement in a hinge adapted for attaching to a stationary body another body swingable relatively thereto, such as a door or the like. The invention is particularly adapted for use in mounting doors on vehicle bodies and the like and has for its object the provision of a hinge which will be simple in structure, economical of manufacture, durable and highly efficient in use.

10 Another object of the invention is the provision of a hinge having a stationary part which is attached to the stationary supporting structure and a swingable part which is attached to the stationary part, so arranged and constructed that

15 the swingable part may be inverted as to position to be used either on a left handed hinge or a right handed hinge.

Another object of the invention is the provision of a hinge of this class whereby the door will be swingably mounted on a supporting structure and movable into tightly closing position in the opening over which it is hung.

Another object of the invention is the provision of a hinge so constructed and arranged whereby 25 a door or the like, when being swung outwardly to open position, will move bodily outwardly for a short distance before beginning its swinging movement on the arms.

Another object of the invention is the provision 30 of a hinge so constructed and arranged that, when mounted in place, all parts will be concealed so that no obstructions or projections will be present on the outer surface.

Another object of the invention is the provision 35 of a hinge so constructed and arranged that when mounted in position it will in no manner mar or interfere with the ornamental appearance of the body.

Another object of the invention is the provision 40 of a hinge so constructed and arranged that it may be mounted on a body in a highly concealed position and thus facilitate the buffing or polishing of the body after the hinge is mounted thereon.

Another object of the invention is the provision 45 of a hinge so constructed and arranged that it will accommodate itself to the distortions of the body, such as a vehicle body is subjected to when in use.

Another object of the invention is the provision 50 of a hinge so constructed and arranged that it will be entirely enclosed when the door is closed and thus protect it from the elements and corrosion and also a hinge which is so constructed

that squeaks and groans may be reduced to a minimum.

Another object of the invention is the provision of a hinge having a stationary part provided with a swingable part pivotally connected to the stationary part by a pair of independently swingable parts.

Another object of the invention is the provision of a hinge having a swingable part which, when swung to open position, will swing on two 10 pivots a portion of its swing and on another set of pivots during the remainder of its swing.

Other objects will appear hereinafter.

The invention consists in the combination and arrangement of parts hereinafter described and 15 claimed.

The invention will be best understood by a reference to the accompanying drawing which forms a part of this specification, and in which,

Fig. 1 is a longitudinal, transverse, sectional view of the invention showing it applied, taken on line 1—1 of Fig. 2.

Fig. 2 is a sectional view taken on line 2—2 of Fig. 1.

Fig. 3 is a sectional view taken on line 3—3 of 25 Fig. 1.

Fig. 4 is a sectional view taken on line 4—4 of Fig. 2 illustrating the swinging movement of the door.

In the drawing I have illustrated the invention used with a stationary body 9, associated with which is the swingable body or door 10. In the body 9 there is formed a recess 11 in which is positioned the U-shaped stationary supporting member 12 having the ends 13 of its legs angularly turned outwardly from each other and secured by screws 14 to the stationary body 9. Connected by the screws 15 to the end face 16 of the door or swingable body 10 is a swingable part 17 of the hinge which is in a general way 30 U-shaped and through one of the legs 17' the screws 15 are projected. The opposite leg 17 is shorter than the leg 17' and is provided with a pair of knuckles 19. Projecting outwardly from these knuckles are arms 20, each of which terminates in a knuckle and through which is directed the pintle 21 which also passes through an opening formed in the arm 22 carried by the pivoted member 23 through which the pintle 24 passes. This pintle 24 also passes through the oppositely 40 disposed legs of the U-shaped member 12 so that the pivoted member 23 is pivotally mounted on the member 12. A pintle 25 passes through the knuckles 19 and also through a knuckle formed in the arm 26 which projects outwardly from the 45 50 55

member 27. This member is tubular and a pintle 28 projects therethrough and also through the oppositely disposed legs of the U-shaped supporting member 12. The members 27 and 23 are substantial duplicates of each other as are likewise the arms 22 and 26. It is thus seen that the swingable part of the hinge, that is the body 17, is pivotally connected to the arm 22 and is adapted to swing on the pivot 21 while the arm 22 also swings on the pintle 24 as a pivot. The body 17 is also connected pivotally to the arm 26 by means of the pintle 25 and the arm 26 is adapted to swing on the pintle 28 as a pivot.

As the door is swung from closed to open position in the initial swinging movement, the door will move outwardly substantially bodily with a very slight swinging, moving from the dotted line position shown in Fig. 4 to the full line position. In this movement the members 23 and 27 are swung on the pintles 24 and 28, respectively, the member 27 swinging slightly more than the member 23, and in this swinging movement the pintle 21 will travel on the circle indicated by the dotted line 36 and the pintle 25 will travel on the circle 37. This movement will continue until the arm 26 approaches closely to the edge of the opening 11 whereupon the member 27 will remain momentarily stationary so that the pintle 25 will provide a momentarily stationary pivot about which the door swings. As this movement continues, the arm 22 is carried farther around in a counter-clockwise direction, thus swinging the body 23. Thus the body 23 continues to swing while the body 27 remains momentarily stationary. This movement will continue until the door approaches fully opened position, whereupon, while the swinging movement of the member 23 continues, the member 27 will be swung inwardly in the opposite direction. Thus, in the opening movement, the arm 26 will swing outwardly until the same lies substantially flush with the edge of the U shaped member 12 where it will remain momentarily stationary for a portion of the swinging and the pintle passing therethrough will form a momentarily stationary pivot. Further swinging will effect inward swinging of the arm 26. The arm 22 will be continued to be swung until it approaches closely to the edge of the U shaped supporting member 12. This movement is indicated in dotted lines in Fig. 1 and the path of travel of the edge of the door is indicated by the dotted line 39 in Fig. 4. In Fig. 1 the hinge is illustrated in full lines in closed position and in dotted lines it is indicated in open position. It is this use of the double swinging action that permits the swinging of the door as described and effects the advantages enumerated herein.

By reversing the position of the hinge, the same may be used either for a right or left swinging hinge.

The swingable part 17 and the stationary supporting member 12 which form the hinge sections are properly termed hinge butts and in some of the claims appended hereto, this descriptive term is used to designate these parts.

It is believed obvious that the various advantages sought are thus obtained and that I have provided an economical, durable hinge possessed of these advantages.

While I have illustrated and described the preferred form of construction, I do not wish to limit myself to the precise details of structure shown, but desire to avail myself of such variations and modifications as may come within the scope of the appended claims.

Having thus described my invention, what I claim as new and desire to secure by Letters Patent is:

1. A hinge of the class described, adapted for mounting a swingable body in position for swingable relation to a stationary body and swingable into alignment therewith comprising; a hinge section adapted for attachment to the stationary body; a U shaped hinge section adapted for attachment at one of its legs to a swingable body, the opposite leg thereof being shorter than the attached leg; an arm projecting outwardly from and angularly to said shorter leg; a pair of arms of equal length, each pivotally mounted at one of its ends on the stationary hinge section, the points of pivot of said arms being spaced apart and in alignment with each other transversely of said stationary hinge section; means for connecting the free end of one of said pair of arms to the shorter leg at the juncture of said leg and said angularly directed arm; and means for pivotally connecting the free end of the other of said pair of arms with the end of said angularly directed arm.

2. A hinge of the class described, adapted for mounting a swingable body in position for swingable relation to a stationary body and swingable into alignment therewith comprising; a hinge section adapted for attachment to the stationary body; a U shaped hinge section adapted for attachment at one of its legs to a swingable body, the opposite leg thereof being shorter than the attached leg; an arm projecting outwardly from and angularly to said shorter leg; a pair of arms of equal length, each pivotally mounted at one of its ends on the stationary hinge section, the points of pivot of said arms being spaced apart and in alignment with each other transversely of said stationary hinge section; means for connecting the free end of one of said pair of arms to the shorter leg at the juncture of said leg and said angularly directed arm; and means for pivotally connecting the free end of the other of said pair of arms with the end of said angularly directed arm, said U-shaped hinge section being faced outwardly in the direction of swinging to outer position.

3. A hinge of the class described, adapted for mounting a swingable body in position for swingable relation to a stationary body and swingable into alignment therewith, comprising: a hinge section adapted for attachment adjacent one end to a swingable body and projecting outwardly from said body, said outwardly projecting end being angularly turned; an arm extending angularly outwardly from said angularly turned end, there being formed in said angularly turned end, at the juncture with said arm, a knuckle, there being a knuckle formed in the outer end of said arm; a pair of arms each pivotally mounted at one of its ends to a stationary hinge section the points of pivot of said arms being spaced apart and positioned adjacent opposite edges of said stationary hinge section; means for connecting the free end of one of said pair of arms to the knuckle of said angularly turned end at said juncture; and means for pivotally connecting the free end of the other of said pair of arms with the knuckle at the outer end of said angularly extended arm, the free ends of each of said pair of arms swinging on an arc passing between the pivots of said pair of arms.

4. A hinge of the class described, adapted for mounting a swingable body in position for swingable relation to a stationary body and swingable

- into alignment therewith, comprising: a stationary hinge section, a pair of arms pivotally mounted at one of their ends in spaced relation to each other on said stationary hinge section adjacent opposite edges thereof; the free ends of said arms swinging on arcs passing between the pivots of said arms; a swingable hinge section adapted for attachment at one end to a swingable body; an angularly turned portion on the opposite end of said section; means for attaching said angularly turned portion pivotally to the free end of one of said arms; an arm projecting angularly outwardly from said angularly turned portion; and means for pivotally connecting the end of said last named arm to the other of said pivotally mounted arms.
5. A hinge of the class described, comprising: a U-shaped supporting body adapted for mounting on a stationary part; a hinge section adapted for mounting on a swingable part associated with said stationary part, said hinge section having an angularly turned leg provided at its end with an outwardly angularly turned portion terminating in a knuckle, there being a knuckle formed at the juncture of said leg and said angularly turned portion; links for pivotally connecting said last-named knuckle to said U-shaped body; and links for pivotally connecting said terminal knuckle to said U-shaped body.
6. A hinge of the class described, adapted for mounting a swingable body in position for swingable relation to a stationary body and swingable into substantial alignment therewith comprising a pair of hinge butts, one being adapted for mounting on one of said bodies and the other on the other of said bodies; a pair of arms pivotally mounted at one of their ends, in spaced relation to each other on one of said butts adjacent opposite edges thereof, the free ends of said arms swinging on arcs passing between the pivots of said arms;
- 10
- 20
- 25
- 30
- 35

an angularly turned portion on the other of said butts; means for attaching said angularly turned portion pivotally to the free end of one of said arms; a laterally offset knuckle-bearing portion on said other butt; and means for pivotally connecting the free end of the other of said pivotally mounted arms to said laterally offset portion.

7. A hinge of the class described, adapted for mounting a swingable body in position for swingable relation to a stationary body and swingable into substantial alignment therewith, comprising a pair of butts; a pair of arms pivotally mounted at one of their ends, in spaced relation to each other on one of said butts adjacent opposite edges thereof, the free ends of said arms swinging on arcs passing between the pivots of said arms; an angularly turned portion on the other of said butts; means for connecting said angularly turned portion pivotally to the free end of one of said arms; an arm projecting outwardly from said last-named butt and terminating in spaced relation to said angularly turned portion; and means for connecting the end of said last-named arm to the other of said pivotally mounted arms.

8. A hinge of the class described, adapted for mounting a swingable body in position for swingable relation to a stationary body and swingable into substantial alignment therewith, comprising a pair of hinge butts; a pair of arms pivotally mounted at one of their ends, in spaced relation to each other on one of said hinge butts, the free ends of said arms swinging on arcs passing between the pivots of said arms; means for pivotally attaching the free end of one of said arms to the other of said butts; and means for pivotally connecting the free end of the other of said pivotally mounted arms to said other butt.

JOHN LUDWIG.
